US0D1047962S

(12) **United States Design Patent** (10) **Patent No.:** **US D1,047,962 S**
(45) **Date of Patent:** **** Oct. 22, 2024**

(54) **HEADSET**

(71) Applicant: **Logitech Europe S.A.**, Lausanne (CH)

(72) Inventors: **Libao Wu**, Fremont, CA (US); **Ethan Wu**, New Taipei (TW); **Yu-Jing Huang**, New Taipei (TW); **Victoria Chiang**, San Francisco, CA (US)

(73) Assignee: **Logitech Europe S.A.**, Lausanne (CH)

(**) Term: **15 Years**

(21) Appl. No.: **29/873,414**

(22) Filed: **Mar. 30, 2023**

(51) LOC (14) Cl. **14-01**

(52) U.S. Cl.

USPC **D14/205**

(58) **Field of Classification Search**

USPC D14/205, 206; D29/112; 2/209; 381/380-381, 374; 362/105

(57) **CLAIM**

The ornamental design for a headset as shown and described.

DESCRIPTION

FIG. 1 is a front perspective view of a headset showing our new design;

FIG. 2 is a second front perspective view thereof;

FIG. 3 is a rear perspective view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a left-side elevation view thereof; and,

FIG. 9 is a right-side elevation view thereof.

The broken lines shown in the figures show unclaimed features of the headset and form no part of the claimed design.

1 Claim, 8 Drawing Sheets
